UNITED STATES PATENT OFFICE.

GEORGE G. BULFINCH, JR., OF BROOKLINE, AND FRANCIS V. BULFINCH, OF DOVER,
MASSACHUSETTS.

BOWLING-GAME APPARATUS.

1,321,593.

Specification of Letters Patent.

Patented Nov. 11, 1919.

Application filed May 19, 1919. Serial No. 298,021.

To all whom it may concern:

Be it known that we, GEORGE G. BULFINCH, Jr., a citizen of the United States, residing at Brookline, county of Norfolk, State of Massachusetts, and FRANCIS V. BULFINCH, residing at Dover, county of Norfolk, State of Massachusetts, have invented an Improvement in Bowling-Game Apparatus, of which the following description, in connection with the accompanying drawing, is a specification, like characters on the drawing representing like parts.

This invention relates to improvements in game apparatus, and the object thereof is to provide a game comprising a series of pins which may be upset by a projectile striking the upper end of one or more of said pins, the pins being so formed and balanced that when struck by the projectile they will be retained in upset position until reset by or for the player.

More specifically the invention comprises an improvement in bowling games and the object thereof is to provide a parlor device upon which a game similar to bowling may be played and in which any one or all of the ten pins may be upset by a suitable projectile, the score of the game being the same as that of the usual ten pin bowling game.

A further object of the invention is to provide a compact apparatus of the character described in which a bowling game may be played without danger or injury to surrounding objects by the bouncing of the projectile.

Another object of the invention is to provide a game apparatus upon which a game may be played analogous to a bowling game in which one or more of a series of pins may be upset by a projectile, said apparatus also comprising a target having means operable when the target is struck to upset all of the pins of the series, thereby making a strike.

A further object of the invention is to provide a pivotally supported pin for a bowling or like game having counterbalancing means whereby the pin may be retained alternatively in playing position or in upset position.

Further objects and features of the invention will more fully appear from the following description and the accompanying drawings and will be pointed out in the annexed claims.

Preferred embodiments of our invention

are illustrated in the accompanying drawing in which—

Figure 1 is a plan view of a bowling apparatus comprising a series of pivotally supported pins adapted when in playing position to have their upper ends converge upwardly and radially,

Fig. 2 is a vertical sectional view on line 2—2, Fig. 1, showing one of the pins in playing position in vertical axial section, and illustrating in dotted lines the pin in upset position,

Fig. 3 is a view partly in vertical section of a modified form of apparatus comprising a series of pins, as illustrated in Fig. 1 with a central target controlling means adapted to upset all of said pins when the central target is struck by the projectile.

The game apparatus embodying our invention, which is illustrated in Figs. 1 and 2 of the accompanying drawings, comprises

preferably a box-like container having a bottom 1 and sides 2, 3, 4, 5 which may be of any form, but which is illustrated herein as rectangular, said sides having secured thereto a suitable support 6 for a series of pins adapted to be upset, the support 6 being spaced apart from the bottom 1 a sufficient distance to avoid the end of the pin striking the bottom when in upset position.

The support 6 has a central, preferably circular, opening 7 over which the series of pins are supported. The pins 8 preferably are in the form of usual bowling pins and have pivotal supports, preferably located slightly below the center of gravity. Any suitable means may be provided for thus pivotally supporting them. As illustrated herein the support comprises a wire bracket, the ends 9, 10 of which are anchored in the supporting plate 6.

The intermediate portions 11, 12 of said wire brackets extend upwardly and substantially radially toward the center of the opening, and are connected by an integral portion 13 extending through or secured to the pin and forming a pivotal support for the pin. Suitable washers 14, 15 may be located upon the portion 13 adjacent the sides of the pin to retain the pin in proper position. The portions 11, 12 of the brackets are desirably so inclined that the base portions of the pins will normally rest upon the support 6, and the upper ends of the pins will converge radially toward the center of the central opening 7. The upper

ends of the pins are desirably located in such close proximity that the projectile, which is used in playing the game, cannot pass between them, so that when the projectile is properly thrown it may simultaneously engage all of the adjacent ends of the pins, thereby upsetting the entire number and producing a "strike."

In order that each pin when upset may be retained in its upset position, means are provided for shifting the center of gravity from one side of the pivotal support to the other. Any suitable counterbalancing means may be provided for this purpose. A convenient means, which is disclosed herewith, comprises a counterweight, such as one or more weights or balls 15 which are loosely contained in a chamber 16 in said pin, which chamber desirably may be formed by boring a hole centrally of the pin from either end to a desired distance and plugging up the end of the hole after the counterweight or counterweights have been introduced in it. It will be obvious that when the counterweights 15 are within the base portion of the pins, as illustrated in full lines in Fig. 2, the pins will be held in playing position, but that when upset the counterweight or counterweights immediately drop to the opposite end of the bore, thereby shifting the center of gravity to the other side of the pivotal support 13, thus retaining the pin in the upset position illustrated in Fig. 2 in dotted lines.

As many players can play the game as may be desired, each player taking his turn. Preferably three balls may be employed as in bowling and each player allowed to throw or toss the three balls for a "box", unless all of the pins are upset with the first ball, which will constitute a "strike", or with the first and second ball, in which case the player will count a "spare", the score of the individual players being kept as in bowling.

By reason of the fact that the pins are thus pivotally supported the bouncing of the projectile will be minimized when it strikes the upper ends of the pins, and consequently there will be less danger of breaking the surrounding objects in the room. Furthermore, the apparatus is such that the ball is required to be tossed so that it will have a downward trajectory and there will be less danger of injury to objects within in games in which the projectile is thrown with force.

In Fig. 3 a modified form of the invention is shown. In this construction, as in the construction illustrated in Fig. 1, the container of the apparatus may be the same box-like construction having a base 1 and sides 2, 3, 4, 5, and a support 6 for the pins provided with a central aperture 7. The pins 17 may be of a construction similar to the pins 8 and may be mounted upon brackets 18 of the same character as the brackets

which support the pins 8. The pin illustrated in Fig. 3, however, differs from the pin shown in Fig. 2 in that the pivotal support for the pin is located more nearly the upper or smaller end of the pin, and the chamber 19 for the counterweight extends downwardly from the smaller end of the pin instead of upwardly from the base end of the pin. The chamber 19 also terminates adjacent the axis upon which the pin is pivoted and does not cross the axis. The operation of the counterweight, however, is the same.

In the construction disclosed in Fig. 3 a central target 20 is provided, which when struck by the projectile will release a mechanism adapted to upset all of the pins simultaneously. The target 20 is supported upon the upper end of a post 21 which is pivotally mounted at its lower end upon a stud 22 carried by suitable brackets 23 secured to the base 1 of the container. A platform 24 preferably of circular form is supported upon a plurality of springs 25, preferably three in number, (although only one is shown) which rest their lower ends upon the base 1 and are retained in place by suitable studs or bolts 26 anchored at their lower ends in the base 1, and having at their upper ends heads which will limit the upward movement of the platform 24 and which extend through the springs and through apertures 27 in the platform 24. Sleeves 28 may be provided to surround the springs 25, said sleeves being of such a length as to limit the downward movement of the platform 24. Upsetting members for the individual pins are carried by the platform 24, and as illustrated herein comprise wire brackets 29 anchored at their lower ends in the platform 24 adjacent its periphery extending upwardly and outwardly beneath the base portions of the respective pins. The post 21 of the target projects through a central opening 30 in the platform 24, and said post is provided with a latch 31 adapted to engage the platform 24 when said post is in vertical position and the platform depressed thereby serving to lock the platform down and the upsetting device 29 in inoperative position so that the pins may be set in playing position.

When the platform 24 is thus locked down, the post 21 being in position vertically, the target 20 will be positioned in the center of the apparatus. The pins will then be set in playing position and the players in playing the game will toss the ball in the manner above described, the object however being mainly to strike the central target 20 in such a manner as to drive it laterally and cause the latch 31 on the post 21 to release its engagement with the platform 24, thereby allowing the platform 24 to be raised upwardly by its springs 25, so that the up-

setting members 29 will act upon the bases of the pins to upset them and produce a "strike". In playing the game, with the apparatus illustrated in Fig. 3, of course, 5 the player counts any individual pin or pins which may be struck by the ball, the score being kept in the same manner as that of the usual bowling game.

It will be understood that the embodiments of the invention disclosed herein are 10 illustrative and not restrictive and that various modifications may be made within the spirit and scope of the accompanying claims.

Having fully described our invention, 15 what we claim as new and desire to secure by Letters Patent, is:

1. A game apparatus comprising a support, a series of pins pivotally mounted thereon having their axes converging to- 20 ward one another, one or more of said pins being adapted to be upset by a projectile impinging upon the converging end or ends.

2. A game apparatus comprising a support having a central annular opening, a 25 series of pins pivotally mounted upon said support with their upper ends converging upwardly and radially, whereby one or more of said pins may be upset by a projectile impinging upon the upper end.

3. A game apparatus comprising a support, a series of pins, means carried by said support pivotally connected to said pins intermediate their ends and normally supporting the same with the upper ends converging, each of said pins being provided with movable counterbalancing means 35 adapted to shift the center of gravity of the pin from one side of the pivot to the other when the pin is upset and to retain said pin 40 in upset position.

4. A game apparatus comprising a support, a series of pins, means carried by said support pivotally connected to said pins intermediate their ends and normally supporting the same with the upper ends converging, each of said pins being provided with an internal chamber and a counterweight 45 movably mounted in said chamber adapted to shift the center of gravity of the pin from one side of the pivot to the other, whereby the pin when upset will remain in upset position and when restored to normal position be retained in said position.

5. A game apparatus comprising a sup- 55 port, a series of pins, means carried by said support pivotally connecting to said pins

intermediate their ends and normally supporting the same with the upper ends converging, each of said pins being provided with an internal chamber and a series of 60 balls in said chamber adapted to shift the center of gravity of the pin from one side of the pivot to the other, whereby the pin when upset will remain in upset position and when restored to normal position be 65 retained in said position.

6. A game apparatus comprising a support, a series of pins pivotally mounted thereon with their upper ends converging upwardly and radially, whereby one or 70 more may be upset by a projectile impinging upon said upper end, a central target, and means operable when said central target is struck by the projectile to upset all of said pins. 75

7. A game apparatus comprising a support, a series of pins pivotally mounted thereon with their upper ends converging upwardly and radially, whereby one or more may be upset by a projectile imping- 80 upon said upper end, a central target, a spring actuated pin upsetting member normally tending to upset all the pins, means connected to said target for retaining said upsetting member in inoperative position 85 but adapted to be released when the central target is struck by the projectile, whereby the upsetting member will be caused by its springs to upset all of said pins.

8. A game apparatus comprising a sup- 90 port, a series of pins pivotally mounted thereon with their upper ends converging upwardly and radially, whereby one or more may be upset by a projectile imping- 95 upon said upper end, a central target 95 comprising a pivotally mounted post, a platform having an aperture receiving said post, springs acting normally to raise said platform, and means carried by said plat- form underlying the lower ends of said pins 100 and adapted, when the platform is raised by its springs, to upset said pins, and means on said target post for locking said plat- form in depressed position, but adapted when said target is struck by the projectile 105 to release said platform, whereby the latter acting under the influence of its springs will upset all of said pins.

In testimony whereof, we have signed our names to this specification.

GEORGE G. BULFINCH, JR.
FRANCIS V. BULFINCH.
